D. MARINSKY

SEMITDETACHED FASTENING DEVICE

Filed Jan. 21, 1925

INVENTOR
Davis Marinsky
BY
Howard C. Thompson
ATTORNEY

UNITED STATES PATENT OFFICE.

DAVIS MARINSKY, OF BRONX, NEW YORK.

SEMITDETACHED FASTENING DEVICE.

Application filed January 21, 1925. Serial No. 3,738.

To all whom it may concern:

Be it known that I, DAVIS MARINSKY, a citizen of the United States, and residing at Bronx, in the county of Bronx and State of New York, have invented certain new and useful Improvements in Semidetached Fastening Devices, of which the following is a specification, such as will enable those skilled in the art to which it appertains to make and use the same.

This invention relates to fastening devices for use in coupling and interlocking two parts or bodies together and particularly to fastening devices of this class wherein the attaching members proper are semi-detached; and the object of the invention is to provide a device of the class and for the purpose specified composed of separate members or parts having interlocking or co-operative elements or links, one end portion of said members or parts being coupled together by the binding element employed and the coupling of said members serving to space the adjacent end portions thereof a predetermined distance from each other; a further object being to provide a device of the class specified which is so constructed as to permit of its use in connection with gloves and similar articles where a predetermined portion of the article or apparel is bound together or of unitary construction; a still further object being to provide a casing or finishing strip for devices of this class composed of material similar to the article or apparel in connection with which the attaching device is employed, or a casing or finishing strip of a color similar to or in harmony with the color of the article or apparel; a still further object being to provide a fastening device of the class described which is so constructed as to facilitate the manufacture of the same especially in the reduction of the manufacturing cost; and with these and other objects in view the invention consists in a device of the class and for the purpose specified constructed as hereinafter described and claimed and in accordance with the method herein set out.

The invention is fully disclosed in the following specification, of which the accompanying drawing forms a part, in which the separate parts of my improvement are designated by suitable reference characters in each of the views, and in which:

Fig. 1 is a plan view of the wrist portion

of a glove showing one of my improved fastening devices mounted in connection therewith and indicating the method of its use;

Fig. 2 is a plan view of a mounting strip 60 illustrating the method of mounting and securing the separate links thereon;

Fig. 2^a is a side view of part of the construction shown in Fig. 2;

Fig. 3 is a plan view of a part of a casing 65 of finishing strip which I employ;

Fig. 4 is a partial section on the line 4—4 of Fig. 1 and on an enlarged scale;

Fig. 5 is a face view of one of the links which I employ; and,

Fig. 6 is a side edge view of the link shown in Fig. 5.

In carrying my invention into effect, I mount upon a strand 10 of suitable material, such for example as fibrous or metallic material, a plurality of links 11, said links being placed side by side and in juxtaposition and being arranged in groups which are spaced apart on said strand, two groups being designated as 12 and 13 in Fig. 2 of the drawing and spaced apart by the strand as shown at 14.

The links 11 in the construction shown are made in accordance with link members as shown, described and claimed in a co-pending application filed by me January 21, 1925, Serial No. 3739, and are composed of a comparatively large and closed loop member 11^a and smaller loop members 11^b and 11^c which are in common axial alinement as 85 clearly shown in Figs. 5 and 6 of the drawing, and the large loop member 11^a is fashioned to form a substantially hook-shaped end portion 11^d.

The strand 10 constitutes a mounting element for the links 11 and is preferably round in cross section and also preferably composed of strong and durable material, such for example as a light cable or wire which is of a size to snugly fit in the apertures formed by the loops 11^b and 11^c, and when the links have been placed on the strand 10 in the manner illustrated in Fig. 2 and arranged in groups, the loops 11^b and 11^c are compressed on the strand 10, said strand being correspondingly compressed as indicated at 15 in Fig. 4 of the drawing to secure the links in position on the strand and to prevent movement of said links relatively thereto. It will be noted that the loops 11^b 110

and 11^c of adjacent links abut one upon the other and the double loop construction serves to equally space the loops 11^a.

I also employ a casing of finishing strip 5 16 having arranged centrally thereof equally spaced apertures 17 through which the loops 11^a of the links are adapted to pass and the apertures 17 are arranged on the strip in groups 18 and 19 separated by a non-aper- 10 tured portion 20.

The number of the apertures 17 in the separate groups 18 and 19 will correspond with the number of links in the separate groups 12 and 13 whereby when the casing or strip 15 16 is mounted upon the strand 14 and the loops 11^a of the links are passed through the apertures 17 of the respective groups, the non-apertered portion 20 will be in alignment with the portion 14 of the strand 10. 20 It will be noted that the side portions of the casing 16 are folded one upon the other after the loops 11^a have been passed therethrough and said side portions are stitched together as indicated at 21 in Fig. 4 of the 25 drawing.

It will be understood from the foregoing description that the strand 10 may be made up in short lengths on which the groups 12 and 13 only are applied or the strand may 30 be made up of indefinite lengths with the groups arranged continuously thereon, the portions 14^a of the strand being cut to subdivide the strand into portions having thereon the groups 12 and 13 of links and the 35 casing or finishing strip may be similarly formed, that is to say, may be made up in lengths suitable for the two groups of apertures 17 or said apertures continuously arranged on said strip, and when the strip has 40 been applied to the strand a fastening device made according to my invention is formed thereby. It will be understood that a suitable coupling block 22 will be employed for moving the links 11 of the separate groups 45 12 and 13 into and out of engagement in the usual manner in devices of this class.

The attaching device formed in the manner above set out may be used in connection with any suitable article or wearing apparel for coupling and uncoupling two parts or bodies and, in the construction shown, in Fig. 1 of the drawing, I have illustrated one method of carrying my invention into effect and have shown in said figure the 50 wrist portion 23 of a glove which is slotted as indicated at 24 in the usual manner to permit of the insertion of the hand into the glove, and the separate side portions 25 and 26 formed by the slot 24 are adapted to be 55 brought together or separated by my improved attaching device. In this use of my invention, the casing or finishing strip 16, or that portion thereof through which the group 12 of links is mounted, is placed upon 60 65 the edge of the side portion 25 and stitched

thereto as indicated at 25^a, and the portion of the strip 16 through which the group 13 of links passes is secured to the side portion 26 by stitching 26^a, it being also noted that the strip 16 extends around the enlarged 70 inner portion of the slit 24 and is stitched to the material of the glove by a continuation of the stitchings 25^a and 26^a, it being understood that said stitchings may be continuous and it is preferred that the material 75 of the glove, or the side portions 25 and 26 thereof is located between the separate side portions of the strip 16 as illustrated in Fig. 4 of the drawing, and in this way said strip 16 forms a finishing strip not only for the attaching device but for the slit portion of the glove, and said strip may be composed of leather similar to the leather employed in the glove or of a fabric similar thereto, or 80 in harmony therewith.

When the attaching device has been mounted in position I provide at the inner end portion thereof means 27 for stopping the inward movement of the coupling block 22 and at the outer end means 28 for limiting the outward movement of said block. It will be understood that when the block 22 is in its innermost position or adjacent to the enlargement of the slit 24 thereof a hand may be inserted into or out of the glove, and in securing the glove in position the block 22 is moved in its outermost position as partially illustrated in Fig. 1 of the drawing, and in the last named position it will be apparent that the hook portions 11^a 95 of the links 11 of one group 12 interlock with the corresponding hook portions of the links of the other group 13 and prevent the separation of the separate groups. 100

It will be understood that while I have shown and described one use of my invention and a specific form of link, that I am not necessarily limited in this respect nor am I limited to any specific method of constructing and assembling the structure herein set out, the distinctive feature of my invention being what I term a semi-detached fastening device and the method of making the same, and various changes in and modifications of the construction herein shown and described may be made, within the scope of the appended claims, without departing from the spirit of my invention or sacrificing its advantages. 105

It will also be apparent that by reason of my improved method of constructing an attaching device and especially when a metallic strand or binder is employed for coupling the separate groups of links together, that a coating or plating of suitable material, as for example, a coating of paint or enamel or metallic coating such as nickel, silver, gold or platinum may be readily applied to the links and to the strand, if desired, by the usual processes and prior 110 115 120 125 130

to the mounting of the fabric strip 16 on said strand, and by reason of this construction the exposed portions of the links, especially, may be colored in harmony with the product in connection with which the attaching device is used or may be given an expensive plating to give the same greater value in some uses of the invention.

Having fully described my invention, 10 what I claim as new and desire to secure by Letters Patent, is:—

1. A device of the class described comprising a strand, a plurality of links mounted on and secured to said strand with the projecting parts of said links in predetermined spaced relation, said links being arranged on said strand in groups and that part of the links of each group mounted on said strand being in juxtaposition and abutting, and the separate groups being coupled one with the other by said strand to form a unitary structure thereof, and an attaching strip adapted to be mounted on said strand and that portion of the links thereon.
2. A device of the class described comprising a strand, a plurality of links mounted on and secured to said strand with the projecting parts of said links in predetermined spaced relation, said links being arranged on said strand in groups and that part of the links of each group mounted on said strand being in juxtaposition and abutting and the separate groups being coupled one with the other by said strand to form a unitary structure thereof, an attaching strip adapted to be mounted on said strand, and means for retaining said strand and links against displacement on said strip.
3. A device of the class described comprising a strand, a plurality of links mounted on and secured to said strand with the projecting parts of said links in predetermined spaced relation, said links being arranged on said strand in groups and that part of the links of each group mounted on said strand being in juxtaposition and abutting and the separate groups being coupled one with the other by said strand to form a unitary structure thereof, and an attaching strip provided with spaced apertures arranged in groups and the links of the separate groups on said strand being adapted to pass through the respective groups of apertures whereby said strip will form a casing for said strand and that portion of the links mounted thereon.

4. A device of the class described comprising a strand of predetermined material, links provided with two loops, said strand being adapted to be passed through one of the loops of said links in mounting the links on said strand, said loops being in juxtaposition and abutting on said strand and said links being arranged on the strand in groups and being secured thereto with

the other loops of the links in spaced relation.

5. A device of the class described comprising a strand of predetermined material, links provided with two loops, said strand being adapted to be passed through one of the loops of said links in mounting the links on said strand, with said loops in juxtaposition and abutting said links being arranged on the strand in groups and being secured thereto with predetermined portions of the links in spaced relation, that portion of the strand between the respective groups serving to couple said groups together to form a unitary structure thereof, and an attaching strip fashioned to receive the projecting portions of the links in the respective groups and to form a casing for said strand.

6. A device of the class described comprising a strand of predetermined material, links provided with two loops, said strand being adapted to be passed through one of the loops of said links in mounting the links on said strand, with said loops in juxtaposition and abutting said links being arranged on the strand in groups and being secured thereto with predetermined portions of the links in spaced relation, that portion of the strand between the respective groups serving to couple said groups together to form a unitary structure thereof, an attaching strip fashioned to receive the projecting portions of the links in the respective groups and to form a casing for said strand, and to provide means for mounting the strand and groups of links in connection with a predetermined support.

7. A fastening device of the class described comprising two coupling bodies secured to a unitary binder and coupled together by said binder, means mounted on said coupling bodies for moving the same into and out of engagement, said coupling bodies comprising independently formed coupling members, mounted on said binder in abutting relation said coupling members being fashioned to interlock when the said bodies are coupled together, and a finishing and attaching strip mounted upon the binder of said bodies and encircling that portion of the coupling members mounted thereon.

8. A fastening device of the class described comprising two coupling bodies secured to a binder composed of a flexible strand and a flexible attaching strip folded around and enclosing said strand, and said bodies being coupled together by said binder.

9. A fastening device of the class described comprising two coupling bodies secured to a binder composed of a flexible strand and a flexible attaching strip folded around and enclosing said strand, and through which parts of the coupling bodies are passed, said bodies being coupled to-

4
gether by said binder, and means mounted on said coupling bodies for moving the same into and out of engagement.

10. A fastening device of the class described comprising two coupling bodies secured to a binder composed of a flexible strand and a flexible attaching strip folded around and enclosing said strand and through which parts of the coupling bodies 10 are passed, said bodies being coupled together by said binder, means mounted on said coupling bodies for moving the same into and out of engagement, and said coupling bodies comprising independently 15 formed coupling members and that part of said members on said strand being in abutting relation.

11. A fastening device of the class described comprising two coupling bodies secured to a binder composed of a flexible strand and a flexible attaching strip folded around and enclosing said strand, and through which parts of the coupling bodies 20 are passed, said bodies being coupled to-

gether by said binder, means mounted on 25 said coupling bodies for moving the same into and out of engagement, said coupling bodies comprising independently formed coupling members, and that part of said members on said strand being in abutting 30 relation and said coupling members being fashioned to interlock when said bodies are coupled together.

12. A fastening device of the class described comprising two coupling bodies secured to a binder composed of flexible material and coupled together thereby, each of said coupling bodies comprising a plurality of independently formed wire link members, and that portion of said link 40 members mounted on said binder being in abutting relation in the separate coupling bodies.

In testimony that I claim the foregoing as my invention I have signed my name this 17th day of Jan. 1925.

DAVIS MARINSKY.
